Henry T. King and Edwin S. Getner, Detroit, Mich., assignors to Chrysler Corporation, Highland Park, Mich., a corporation of Delaware

Application July 22, 1954, Serial No. 31,537

Term of patent 7 years

(Cl. D14—6)

Fig. 1 is a front elevational view of an automobile stone shield showing our new design; and

Figs. 2, 3, 4, 5, 6 and 7 are sectional views taken on the lines 2—2, 3—3, 4—4, 5—5, 6—6 and 7—7 respectively of Fig. 1.

The characteristic features of our design reside in the portions shown by means of full lines in the drawing.

We claim:

The ornamental design for an automobile stone shield, substantially as shown and described.
